UNITED STATES PATENT OFFICE.

CHARLES W. JUSTUS, OF LIMA, OHIO, ASSIGNOR OF ONE-HALF TO
ALBERT BENROTH, OF BLUFFTON, OHIO.

LAND-ANCHOR.

SPECIFICATION forming part of Letters Patent No. 756,374, dated April 5, 1904.

Application filed December 21, 1903. Serial No. 186,076. (No model.)

To all whom it may concern:

Be it known that I, CHARLES W. JUSTUS, a citizen of the United States, residing at Lima, in the county of Allen and State of Ohio, have 5 invented certain new and useful Improvements in Land-Anchors; and I do declare the following to be a full, clear, and exact description of the invention, such as will enable others skilled in the art to which it appertains to make and 10 use the same.

This invention relates to improvements in land-anchors.

The object of the invention is to provide an anchor of this character which may be expanded after being inserted in the ground, thereby preventing the withdrawal of the anchor. 15

A further object is to provide a land-anchor which will be strong and durable, reliable, and 20 well adapted to the purpose for which it is designed.

With these and other objects in view the invention consists of certain novel features of construction, combination, and arrangement 25 of parts, as will be more fully described, and particularly pointed out in the appended claims.

In the accompanying drawings, Figure 1 is 30 a side view of the anchor, showing the parts in their contracted position. Fig. 2 is a similar view showing the parts in their expanded position. Fig. 3 is a central vertical sectional view of Fig. 2. Fig. 4 is a top plan view of the device with the parts expanded, as shown 35 in Fig. 2. Fig. 5 is a horizontal sectional view taken above the expanding-cone on the line 5 5 of Fig. 2.

In the embodiment of the invention I provide a centrally-disposed operating-rod 1, 40 formed on its lower end with a head 2 and on its upper end with an eye 3. On the rod 1 is slidably mounted a circular disk or head 4. In said disk are formed slots 5, which are arranged at diametrically opposite points. The 45 outer walls 6 of each of the slots 5 are cut-away and rounded to form bearing-surfaces. The edges of the disk 4 are beveled or rounded off, as shown, so that the same will more readily enter the ground.

In each of the slots 5 are arranged the curved 50 upper ends 7 of expandable arms 8. Said curved ends are adapted to bear on the rounded surfaces of the outer walls 6 to loosely support the arms 8. On the inner side of the upper end of each of the arms 8 are formed 55 lugs 9, which are adapted to bear under the disk or head 4, and on the inner sides of the lower ends of the arms are formed inclined or beveled bearing-surfaces 10. On the outer sides of the lower ends of the arms are formed 60 radially-disposed segmental blades 12, which are beveled outwardly to an edge, as shown.

On the lower end of the rod 1 is slidably mounted a hollow expanding-cone 13, which is engaged on its inner side by the head 2 on 65 said rod. On the lower end of the cone 13 is arranged an annular flange 14, which forms a stop for the lower ends of the arms 8 when in their expanded positions. The outer edge of the flange 14 is beveled or rounded off to 70 facilitate the passage of the cone into the ground.

In the rod 1 above the head or disk 4 is formed a hole, in which is inserted a pin 16 to form a stop, which is engaged by the head or 75 disk 4 when the arms 8 are in their contracted positions.

In operation, assuming the parts to be in their contracted positions, as shown in Fig. 1, a hole is bored in the ground of about the same 80 diameter as the widest part of the anchor. This hole may be of any suitable depth sufficient to hold, and into the same is inserted the anchor with the parts contracted, as shown in Fig. 1. The anchor is inserted until the end 8 of the cone strikes the bottom of the hole. The end of the rod is now struck with a hammer, which will drive the same downwardly to a slight degree and, owing to the engagement of the pin 16 with the disk or head 4, will force said disk inwardly into engagement with the lugs 9, and thereby force the arms 8 downwardly to a slight degree and cause the same to be expanded by the upper end of the cone 13 sufficiently to hold the anchor in place. The rod 1 is now drawn outwardly, which will cause the head 2 thereon to engage the cone 13 and draw the same outwardly, which will spread

or expand the arms 8 and force the blades 12 into the solid earth forming the walls of the hole in which the anchor was inserted, thus securely fastening the anchor in the ground and preventing the withdrawal of the same. The flange 14, forms the stop on the lower end of the cone which when the arms are expanded limits the expansion of the arms 8 by the cone, thereby relieving the arms of all lateral strain and applying the pull to the end of the anchor, as will be understood. After the anchor is thus firmly embedded guy-wires may be secured in the eye 3 on the end of the rod to securely hold the same. The anchor will be found useful in connecting the brace or guy wires of telegraph and telephone poles, fence-posts, and the like.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. In a device of the character described, the combination with a centrally-disposed operating-rod, of a disk or head slidably mounted on said rod, expandible members carried by said head, means whereby said members are given an initial expansive movement to hold the anchor in place, means for further expanding said members to firmly anchor the device and means for limiting said expansion, substantially as described.

2. In a device of the character described,

the combination with a centrally-disposed operating-rod, a disk or head slidably mounted on said rod, arms pivotally mounted at their upper ends in said disk or head, blades formed on the lower end of said arms, an expanding-cone slidably mounted on the lower end of said rod to expand said arms and blades, substantially as described. 45

3. In a device of the character described, 50 the combination with a centrally-disposed operating-rod, a disk or head slidably mounted on said rod, arms pivotally mounted at their upper ends in said disk or head, blades formed on the lower end of said arms, an expanding-cone slidably mounted on the lower end of said rod to expand said arms and blades, an annular flange formed on said cone to engage the lower ends of said arms, thereby limiting the expansion of and relieving the strain on said arms, substantially as described. 55

4. In a device of the character described, 60 the combination with a centrally-disposed operating-rod, a disk or head slidably mounted on said rod, arms pivotally mounted at their upper ends in said disk or head, blades formed on the lower end of said arms, an expanding-cone slidably mounted on the lower end of said rod to expand said arms and blades, lugs formed on the upper end of said arms, and a 65 stop-pin arranged in said rod whereby an initial expansive movement may be given to said arms and blades, and means for limiting the expansion of and relieving the strain on said arms, substantially as described. 70

In testimony whereof I have hereunto set my hand in presence of two subscribing witnesses.

CHARLES W. JUSTUS.
